UNITED STATES PATENT OFFICE.

CHARLES VALLONE, OF BUFFALO, NEW YORK, ASSIGNOR TO BARCALO MANUFACTURING COMPANY, OF BUFFALO, NEW YORK.

CRIB OR BED AND THE LIKE STRUCTURE.

Application filed September 26, 1925. Serial No. 58904.

This invention relates to improvements in children's cribs or beds and the like structures, and particularly to that class of such cribs having side frames or panels provided 5 with a lower stationary section and an upper section pivotally connected with and movable relative to the lower section, whereby it may occupy either a position above and in the vertical plane of the lower section, or 10 so that it may be dropped or swung downwardly to a position alongside said sections to give access to the inside of the crib.

In structures of this character heretofore provided the hinges or pivotal connections 15 between the sections, and the fastening or securing devices for holding the movable sections in their upper or operative position have been such as to permit relative movements and consequent rattling and noise between the parts during the use of the crib, and further, in some cases the securing devices have been so formed that the child occupying the crib could release the movable section.

25 The principal objects of the present invention are to construct a side frame for cribs and the like having an improved hinge or pivotal connection between the stationary and the movable section of the side frame, 30 which is substantially noiseless in use and operates easily and smoothly; also to provide an improved keeper, latch or securing device which is adapted to maintain the movable section in its upper operative position 35 and is readily operable by persons other than a child occupying the crib to release the section or secure the same in operative position, but is so constructed that, under ordinary conditions, a child would be unable 40 to effect the release of the movable section; also to construct a hinge or pivotal connection for the movable section adapted to co- 45 operate with the improved keeper of this invention, and which is adapted to permit a limited upward and downward movement of the movable section for releasing or engaging the same from or with the securing device, in addition to a swinging movement of said section about said stationary section; also to construct a hinge connection for 50 this purpose having positive stop means of novel construction for holding the movable section in operative position, and which also is adapted to limit the movement of the section in a direction to release the same from

the keeper, and also acts to positively limit the downward swinging movement of the section when moved to its open position and which also acts to prevent the section from striking or rattling against the lower section; also to provide a hinge connection of this kind which is so constructed as to hold the movable hinge section at a distance from the fixed side frame of the crib to prevent 60 injury, such as pinching of fingers, of the occupant of the crib or of the attendant; also to provide a hinge connection for the sections of the side frame consisting of few parts of simple construction, preferably in the form of inexpensive sheet metal stampings, adapted to be assembled and secured to the crib at a minimum of expense.

65 The upper and lower sections of the side frames or panels for cribs of this character are usually of like or substantially similar construction. For instance, the sections are often each formed of a horizontal upper and lower rail connected by fillers extending in the same general direction in each section, and it has been found that in such cases the 70 general appearance of the crib has been marred by the occurrence of slight discrepancies or errors in manufacture, such as a misalignment of one or more bars or rods which would be accentuated or made 75 particularly noticeable when the movable panel is in open position.

80 A further object, therefore, of the present invention is to construct a side frame for cribs in which the horizontal bars of the upper and lower sections are connected by fillers or members of contrasting character or of different design, so that slight 85 discrepancies or errors of manufacture will not be noticeable.

85 Other objects of the invention are to improve and simplify the construction, and reduce the cost of manufacture of children's cribs in the other respects hereinafter specified and claimed.

90 In the accompanying drawings,
Fig. 1 is a side elevation of a child's crib showing a side frame including a stationary section and a movable section, and connecting means and securing devices for said 105 movable section embodying the invention.

95 Fig. 2 is a similar view showing the movable section of the side frame in its lower position.

100 Fig. 3 is a transverse, sectional elevation, 110

on an enlarged scale, on line 3—3, Fig. 1, showing the movable section of the side frame in its upper or operative position.

Fig. 4 is a similar view showing the side frame moved upwardly to release the same from its upright or operative position.

Fig. 5 is a sectional elevation, on an enlarged scale, on line 5—5, Fig. 2, showing the movable section in its lower position.

10 Fig. 6 is an enlarged sectional elevation on line 6—6, Fig. 1, showing the improved pivotal connection between the movable and stationary sections of the side frame.

Fig. 7 is a horizontal section on line 7—7, 15 Fig. 6, of the pivotal connection for the movable section.

Fig. 8 is an enlarged sectional elevation showing one of the securing devices or keepers for the movable section of the side frame.

20 Fig. 9 is an enlarged vertical section of the keeper and adjacent parts of the crib, on line 9—9, Fig. 8.

Fig. 10 is a perspective view, detached, of one of the keepers or securing devices.

25 The crib shown in the drawings comprises, as usual, upright, stationary end frames or members provided with tubular corner posts 12, said frames being secured together by longitudinal side rails 13 and which may also

30 form the side rails of the mattress frame. The spaces above the rails 13 and between the posts 12 are closed by side frames, one or both of which includes a lower fixed or stationary section or frame 14 formed of top 35 and bottom horizontal tubes or rails 15 and 16 connected together in any suitable manner, such as by the spaced, vertical rods 17 and preferably having the ends of the rails 15 and 16 rigidly attached to the end frames

40 12. The side frame further comprises an upper section or frame 20, adapted to extend above and in the vertical plane of the lower section when in operative position, and which is pivotally connected to the lower

45 section so as to swing outwardly and downwardly alongside the same when access into the inside of the crib is desired. The section 20 is provided with top and bottom horizontal tubes or rails 21 and 22, and, in ac-

50 cordance with the present invention, these rails are connected together by fillers or members of different character to those used for the lower sections 14, such, for instance, as the rods 23, 23a and 24, shown in Figs. 1 and 2. This feature of the invention will

55 be later referred to and more fully explained. The bottom rail 22 of the upper, movable section 20 is pivotally secured to the top rail 15 of the lower section 14 by connecting devices 25 constructed in accordance with this invention, preferably disposed one at each end of the section. The extremities of the top rail 21 of the section 20 are adapted to engage and be releasably secured in

60 keepers or securing devices 26, one of which

is fixed to each corner post 12 and is constructed and adapted, in accordance with this invention, to cooperate with the pivotal connections 25 to permit the upper section 20 to be releasably maintained in operative 70 position as shown in Fig. 1, and so that said section may be moved a short distance upwardly to release the same from the keepers and permit the section 20 to be swung downwardly alongside of the lower section 14 as 75 shown in Figs. 2 and 5.

In accordance with the invention, each of the pivotal devices or connections 25 is in the form of a three section, or double pivot hinge, and, as shown, comprises an 80 upwardly extending arm or part 30 rigidly secured to the top horizontal rail 15 of the stationary section 14, a downwardly extending and forwardly offset arm or part 31 rigidly secured to the bottom horizontal rail 85 22 of the movable section 20, with its lower end extending in front of, and adjacent to, the upper end of the arm 30. A movable link 32 is pivotally connected to said ends of the arms 30 and 31, respectively, as by means 90 of the pivots or studs 33 and 34.

The keepers 26 for the movable section 20 are each preferably formed of a single, sheet metal stamping and comprise a transverse, vertical plate having a body portion 36 spaced a short distance from the inner side of a post 12, and which is provided with an upper, offset, horizontal end portion 37 formed with a reduced lug 38 extending upwardly therefrom and forming stop 100 shoulders 39 on the end 37. The lug 38 is adapted to be inserted into a hole 40 in the wall of the tubular end post with the stop shoulders 39 abutting against the post 12, and the plate is further provided with another offset end portion 41 terminating in a downwardly extending lug 42 adapted to abut against and be secured to the adjacent face of the post 12, as by a rivet or other attaching device 43, see Fig. 10.

105 By providing the lug 38 and stop shoulders 39, the keeper 26 is adapted to be secured to the post 12 by the single rivet 43 passing through lug 42, but obviously the keeper could be secured to the post 12 by any 110 other suitable means.

115 The body portion 36 of the plate is formed with an irregular recess or slot having a horizontal portion 45 extending to the front or outer edge of the plate, and a downwardly extending closed portion 46 terminating in a bottom stop or seat 47, said portion 46 being connected to the horizontal portion 45 by a rearwardly extending offset portion 48, so formed or proportioned as to provide a rearwardly extending stop shoulder 50 adapted to overhang the portion 46 of the slot. The rear edge or wall of the portion 48 is adapted to form a stop 51.

120 The upper swinging section 20 of the side 130

frame is provided at each end with a relatively fixed finger or part adapted to be engaged with and released from an adjacent keeper 26. In the construction shown each 5 end of the horizontal top rail 21 of the upper section 20 is formed or provided with an integral finger or reduced part 53 extending longitudinally therefrom, and in the upper or closed position of the section 10 20, each finger 53 extends into the recess of the adjacent keeper and rests on the bottom stop or seat 47. In this position, the links 32 of the pivotal connections 25 extend substantially horizontally as shown in 15 Figs. 3 and 6. In order to move the fingers 53 out of the recesses in the keepers 26 to lower the section 20, it is necessary to lift the rail 21 first upwardly out of the portion 46 of said recesses, then rearwardly through 20 the portions 48 in order to pass the overhanging stop shoulder 50, this rearward movement, however, being limited by the stop 51, and thence upwardly and forwardly through the horizontal open portion 45 25 of the recess, see Fig. 4. This movement of the rail 21 of the section 20 is permitted by the double pivot connection between the links 32 and the arms 30 and 31, the links 32 swinging upwardly about the pivots 33, see Fig. 4. The distance between the pivots 33 and 34 is substantially equal to or 30 slightly greater than the distance from the bottom of the portion 46 of the recess and the open end of the portion 45 of said recess, 35 so that the section 20 is permitted to move as a whole without binding or straining the pivotal connections or parts of the crib. When the section 20 has been moved to the 40 position shown in Fig. 4, as just explained, it may be easily lowered by an outward and downward movement to a position alongside the lower section 14 as shown in Figs. 2 and 5, the links 32 swinging back to their horizontal positions on their pivots 33 during 45 this movement, so that during the last part of said downward movement, the section 20 swings about the other pivots 34.

In order to prevent the section 20 from 50 striking or rattling against the section 14 when in lowered position, stop means or abutments are provided which are adapted to abut and positively hold the section 20 in spaced relation to said lower section. For this purpose in the construction shown, 55 the edge 55 of the fixed arm 30, and the edge 56 on the offset arm 31 of each connection 25 are utilized, these edges engaging or abutting against each other to limit the movement of the section 20 inwardly to- 60 wards the section 14 as shown in Fig. 5. As the arms 30 and 31 are rigidly secured to the rails 15 and 22 respectively, no further inward movement of the swinging section 20 can occur after said faces 55 and 56 are in 65 contact, so that there can be no rattling or

striking of the swinging section 20 against the fixed side frame section 14.

It is desirable to maintain the lower end of the section 20 in a relatively stationary position with reference to the section 14 70 when said section 20 is in its upper or operative position so that the same is prevented from swinging or rattling, and it is also desirable to limit the upward movement of said section 20 when disengaging the same 75 from the keepers 26, in order to prevent the links 32 from swinging the pivots 34 up to or beyond the dead center position relatively to the pivots 33 and thus interfering with the lowering of said section 20.

To effect these results, stop means are provided, which in the construction shown, comprises a stop or projection 58 formed on, or secured to each link 32, and extending laterally from one face thereof into the plane of the arms 30 and 31, see Fig. 8, and adapted to engage with stop shoulders 59 and 60 formed by cutting away or recessing one end of the arm 30. In the operative or latched position of the section 20, each stop 58 is adapted to rest on the stop shoulder 59 and when the link 32 is swung upwardly about the pivot 33 the stop projection 58 engages the other stop shoulder 60 which is so positioned that the link 32 cannot swing into a dead center position with reference to the pivot 33, see Fig. 4.

The stop or projection 58 on the link 32 is preferably formed by striking out or upsetting a portion of the metal of the arm, thus obviating the labor and cost of securing a separate stop pin or other member to the link.

The arms 30, 31 may be rigidly secured to the respective rails 15 and 22 so as to extend transversely thereof in any suitable manner, but preferably are secured by means of an integral shank or stud 62 extending endwise in the plane of the arms and adapted to enter holes in the rails so that their ends may be riveted against the opposite faces of said rails. In order to prevent the turning or displacement of the arms relatively to the rails to which they are secured, each arm is provided, adjacent the shank 62 with a curved shoulder or edge 63 formed concentrically with the outside of the tubular rail, and which is adapted to extend transversely across and be drawn tightly against the rail when the shank 62 is passed therethrough and secured, so that the arm is rigidly held in transverse relation to the rail.

By forming the pivotal connections 25 of flat parts, pivoted together with their flat faces in engagement, and connecting the arms 30 and 31 rigidly to the sections 14 and 20 respectively, and by forming the fingers 53 of the top bar 22 of the movable section 30 so as to fit snugly on the seats 47 in the 130

recesses of the keepers 26, practically no play can occur between the parts of the side frame, and the movable section is held stationary when in its upper position so that noise and rattling is prevented when the crib is in use. By forming each keeper of a single piece and rigidly connecting it to a corner post, the noiseless feature of the crib is further ensured.

10 By making the arm 31 of offset form, as shown, with the offset 65, the swinging crib section 20, when in its lower position is spaced at a distance from the fixed section 14 so that there is no danger of pinching a child's fingers between the bars 15 and 22, as may be clearly seen by referring to Fig. 5, and all possibility of contact between the sections 14 and 20 is eliminated, which prevents noises or rattling and also prevents damage to the finish of the crib.

As shown in Figs. 1 and 2, the top and bottom rails 21 and 22 of the upper movable section 20 are connected by fillers or rods 23, 23a and 24, as previously stated. By forming this section with fillers of different design to that of the fillers 17 of the section 14, or which are of different character or appearance from the fillers used in the other section 14, the appearance of the side frame 30 will not be marred by slight discrepancies in manufacture should they occur, as would be the case, for instance, if the rails 21, 22 were connected by upright rods, spaced substantially as in the section 14. Such slight 35 discrepancies in manufacture might not be noticeable when the movable top section of the crib is in its upper position, but would be greatly accentuated and become decidedly conspicuous when this section is in its lower 40 position in front of the stationary section of the side frame. Consequently, a crib of the kind described might become unsaleable because of slight faults of manufacture which would not in any way impair the usefulness 45 or durability of the crib, but by arranging the filler rods or members which connect the horizontal rails of one of the sections in a different pattern relatively to the fillers of the other section, a pleasing appearance is 50 assured even if slight faults or inaccuracies of manufacture occur.

Obviously, the connecting rods or members may be arranged in other ways than those shown in the drawings in either the lower or 55 upper sections 14 and 20, as desired.

I claim as my invention:

1. In a side frame for a crib or the like, the combination of an upright stationary section, a movable section adapted to occupy an 60 upright, operative position above and adjacent said stationary section, securing means for holding said movable section in said upright position and which is constructed to permit said section to be released therefrom by an upward and forward movement to

swing to a downwardly extending, inoperative position alongside said stationary section, and a hinge connection between said sections which is constructed to permit such movements, said hinge comprising a fixed arm extending upwardly from the top of said stationary section, a fixed arm extending outwardly and downwardly from the bottom of said movable section and having its free end offset and extending downwardly, said other arm having its end disposed in horizontal alinement with said offset end of said second arm and both of said ends being arranged in a vertical transverse plane, a transverse link disposed alongside of, and 70 pivotally connected to the ends of said arms, a stop on said link extending laterally therefrom into said plane of said arms, and a stop shoulder on said first mentioned arm adapted to be engaged by said stop on said link to hold said movable section in upright, operative position, and a second stop shoulder on said arm also adapted to be engaged by said stop on said link to limit said upward releasing movement of said section. 75

2. In a side frame for a crib or the like, the combination of an upright stationary section, a movable section adapted to occupy an upright, operative position above and adjacent said stationary section, securing means for holding said movable section in said upright position and which is constructed to permit said section to be released therefrom by an upward and forward movement and then to swing to a downwardly extending, inoperative position alongside said stationary section, and a hinge connection between said sections which is constructed to permit such movements, said hinge comprising a fixed arm extending upwardly from the top of said stationary section, a fixed arm extending outwardly and downwardly from the bottom of said movable section and having its free end offset and extending downwardly, said other arm having its end disposed in horizontal alinement with said offset end of said second arm and both of said ends being arranged in a vertical transverse plane, a transverse link disposed alongside of and pivotally connected to said ends of said arms, and cooperating faces on each of said fixed arms which are adapted to abut when said movable section is swung downwardly so as to limit such movement, and said faces also acting to positively hold said movable section in spaced relation to said stationary section. 90

3. In a side frame for a crib or the like, the combination of an upright stationary section, a movable section adapted to occupy an upright, operative position above, and adjacent said stationary section, securing means for holding said movable section in said upright position and which is constructed to permit said section to be released 100

therefrom by an upward and forward movement to swing to a downwardly extending inoperative position alongside said stationary section, each of said sections having a frame portion adjacent the other section, a hinge connection between said sections which is constructed to permit such movements, said hinge comprising a pair of oppositely extending sheet metal arms, one of which is secured to and extends transversely of the frame portion of each section, a pair of stop shoulders on one of said arms, and a sheet metal link pivotally connected to said arms and having an integral stop extending into the plane of said arms and adapted to engage one of said stop shoulders to hold said movable section stationary while in upright operative position, said stop being also engageable with the other stop shoulder to limit the upward releasing movement of said section.

4. In a side frame for a crib or the like, the combination of an upright stationary section, a movable section adapted to occupy an upright, operative position above and adjacent said stationary section, securing means for holding said movable section in said upright position, a hinge connection between said sections comprising a pair of oppositely extending sheet metal arms, one of which is secured to and extends transversely of the frame portion of each section, a pair of stop shoulders on one of said arms, a sheet metal link pivotally connected to said arms and having an integral stop extending into the plane of said arms and adapted to engage one of said stop shoulders to hold said movable section stationary while in upright operative position, said stop being also engageable with the other stop shoulder to limit upward movement of said section, and said arms each having a side edge, one of which abuts against the other when said movable section is swung downwardly to its inoperative position to limit such movement and to positively hold said section out of contact with said stationary section.

5. A crib or the like having a stationary side section and a movable section, a stationary securing device on said crib having an irregular open slot, a fixed part on said movable section formed to engage in said slot to maintain said section in upright operative relation to and above said stationary section, said fixed part on said movable section being disengageable from said slot by a tortuous upward and outward movement to release said movable section, and a hinge connection between said sections which is constructed to cooperate in the movements of said movable section and permit the latter to be released from or engaged with said securing device and which also permits said

section to swing about said hinge to a depending position alongside said stationary section, said hinge connection comprising a fixed arm extending upwardly from the top of said stationary section, a fixed arm extending outwardly and downwardly from the bottom of said movable section and having its free end offset and extending downwardly, said other arm having its end disposed in horizontal alinement with said offset end of said second arm and both of said ends being arranged in a vertical transverse plane, a transverse link disposed alongside of and pivotally connected to said ends of said arms, a stop on said link extending laterally therefrom into the plane of said arms, and a stop shoulder on said first mentioned arm adapted to be engaged by said stop on said link to hold said movable section in upright operative position, and a second stop shoulder on said arm also adapted to be engaged by said stop on said link to limit said upward releasing movement of said section.

6. A crib or the like having a stationary side section and a movable section, a stationary securing device on said crib having an irregular open slot, a fixed part on said movable section formed to engage in said slot to maintain said section in upright operative relation to and above said stationary section, said fixed part on said movable section being disengageable from said slot by a tortuous upward and outward movement to release said movable section, and a hinge connection between said sections which is constructed to cooperate in the movements of said movable section and permit the latter to be released from or engaged with said securing device, and which also permits said section to swing about said hinge to a depending position alongside said stationary section, said hinge connection comprising a fixed arm extending upwardly from the top of said stationary section, a fixed arm extending outwardly and downwardly from the bottom of said movable section and having its free end offset and extending downwardly, said other arm having its end disposed in horizontal alinement with said offset end of said second arm and both of said ends being arranged in a vertical transverse plane, a transverse link disposed alongside of and pivotally connected to said ends of said arms, and cooperating faces on each of said fixed arms which are adapted to abut when said movable section is swung downwardly so as to limit such movement, and said faces also acting to positively hold said movable section in spaced relation to said stationary section.
